UNITED STATES PATENT OFFICE.

STEPHEN O. BRYANT, OF BETHANY, MISSOURI.

SNAKE-POISON EXTRACTOR.

Application filed August 26, 1921. Serial No. 495,686.

To all whom it may concern:

Be it known that STEPHEN O. BRYANT, a citizen of the United States of America, residing at Bethany, in the county of Harrison and State of Missouri, has invented new and useful Improvements in Snake-Poison Extractors, of which the following is a specification.

The object of the invention is to provide 10 a simple and effective means for extracting the poison due to snake and other bites from the wound as an emergency means of preventing the poison from passing into the blood circulation of the victim and as a substitute for the method occasionally followed 15 of sucking the wound with the attendant risk to the person who resorts to this expedient and which usually proves fatal in the event that there should be any cut or abrasion of the lips of the person applying such remedy; and with this object in view the invention consists in a construction and combination of parts of which a preferred embodiment is shown in the accompanying 20 drawings, wherein:—

Figure 1 is a side view, and

Figure 2 is a longitudinal sectional view of an instrument embodying the invention.

Figure 3 is a transverse sectional view of 30 the same.

Figure 4 is a view partly in side elevation and partly in section showing a modification of the invention such as will obtain in the manufacture of the invention in small 35 units.

The device consists of a cylindrical or tubular body 10 and a vacuum chamber 18, this body preferably having a flared mouth piece 11 for arrangement in air tight contact with the surface of the body of the victim around the abrasion formed by the bite or stroke of the snake or other animal. This mouth piece is preferably of rubber to permit of compression to enable the engagement 40 on parts of the body on which a strong suction could not be obtained if the mouth piece were of metal, although on fleshy parts of the body a metal mouth piece would serve the purpose of the invention.

The body portion 18 is formed adjacent 50 the mouth piece with a laterally disposed vacuum cup in communication with the vacuum chamber and constituting an internally threaded cap engaged with a nipple formed on the vacuum chamber.

As a means for exhausting the air from

the vacuum chamber, a pump is employed and consists of a tubular element 10 secured to the vacuum cup by the lateral members 10^a and 10^b of which the former is of tubular form and is provided with a valve 19 closing communication between the tubular member 10 and the vacuum chamber 18, a stop 20 being mounted in the member 10 to preclude too great an opening movement of 60 the valve 19. A flange 13 is mounted in the tubular body 10 and provided with a stem 14 terminating in a ring or similar hole 15 beyond the rear end of the tubular member, this ring serving as a means to 70 permit the operation of the plunger. The plunger is provided with a flexible packing disk 16 designed to fold rearwardly during the forward stroke of the plunger to spread and form an air tight contact with the surface of the barrel on the return or operative stroke, so as to produce a forcible suction to exhaust the air from the vacuum chamber and consequently produce a suction in 75 the flared mouth piece to extract venom or 80 poison from the wound for reception by the venom cup 12.

In the operation of the invention the flared mouth piece is placed over the wound and the operation of the pump immediately 85 begun. Air is thus extracted from the vacuum chamber 18 by the pump with the result that a suction is created on the wound and the poison extracted from the latter passed to the vacuum chamber and removed 90 from the venom cup in which it falls. After the completion of the operation of extracting the poison, the slight loosening of the cap constituting the venom cup will admit enough air to the vacuum chamber to 95 relieve the suction on the wound and thus permit the ready withdrawal of the mouth 11 from the wound.

In Figure 4 there is shown a modification of the invention in which the venom cup 100 and the pump are combined. The tubular member 18' carries the plunger 13' and the latter is provided with a stem 14' protruding through the rear of the tubular member 18' to permit the manipulation of the 105 plunger to create a vacuum in the tubular member and thus a suction in the discharge mouth 11'.

Having described the invention, what is claimed as new and useful is:—

A poison extractor comprising a cylindrical barrel closed at one end and open at

its opposite end, a cone shaped mouth piece inserted in the open end of the barrel and having its axis in longitudinal alinement with the axis of the barrel, said mouth piece being composed of relatively rigid material and having tapered walls which are thickest at the inner smaller end of the mouth piece, the parts being so arranged that the barrel may be used as a handle for forcing the larger end of the mouth piece into the

flesh whereby the wound therein is forced up into the mouthpiece and opened, means for rarifying the air in the barrel and a venom cup projecting laterally from the barrel adjacent the mouth piece and communicating interiorly with the barrel.

In testimony whereof he affixes his signature.

STEPHEN O. BRYANT.
